(57) **CLAIM**

The ornamental design for stationary spin cycle, as shown and described.

DESCRIPTION

FIG. 1 is a perspective view of a stationary spin cycle of the present design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in FIGS. 1–7 illustrate unclaimed portions of the design. The broken lines showings of the pedals and the cylindrical member at the base of the design are provided purposes of environment and form no part of the claimed design.
